United States Patent Office

Des. 198,671
Patented July 21, 1964

198,671

CABANA

Resta S. Gregoire, Dillsburg, Pa., assignor to Gregoire
Engineering and Development Company, Adelphi, Md., a corporation of Maryland

Filed Aug. 6, 1962, Ser. No. 71,194

Term of patent 14 years

(Cl. D13—1)

FIG. 1

FIG. 3

FIG. 1 is a perspective view of a cabana showing my new design, the opposite side thereof having substantially the same appearance except for the absence of a door;

FIG. 2 is a front perspective view thereof with the door in open position, and

FIG. 3 is a top plan view thereof.

I claim:

The ornamental design for a cabana, substantially as shown and described.
